UNITED STATES PATENT OFFICE.

ARNOLD NACKE, OF PHILADELPHIA, PENNSYLVANIA, ASSIGNOR OF ONE-HALF TO ISIDOR KITSEE, OF PHILADELPHIA, PENNSYLVANIA.

PLATFORM FOR POWER-MOTORS.

No. 901,025.

Specification of Letters Patent.

Patented Oct. 13, 1908.

Application filed May 27, 1905. Serial No. 262,639.

To all whom it may concern:

Be it known that I, ARNOLD NACKE, of the city and county of Philadelphia, State of Pennsylvania, have invented certain new and useful Improvements in Platforms for Power-Motors, (Case No. 259,) of which the following is a specification.

My invention relates to an improvement in swinging platforms and has more special reference to platforms for power motors, such for instance as gas engines, etc. In cases where such power motors are placed in a building, the vibration caused by the operation of this motor is such as to bar the general employment of same in the upper floors of such buildings. To overcome this difficulty I have recourse to the arrangements and features as will hereinafter be more fully described, illustrated in the drawing, and more particularly pointed out in the claims following the specification.

Referring to the drawing:—Figure 1 is a perspective view of a platform secured in accordance with my invention. Fig. 2 is a partial sectional and partial perspective view of that part of the lower portion of the platform which is secured, in accordance with my invention, to the wall of the building.

A is the platform as an entirety; B is the lower portion of same, or platform proper, on which the power motor is adapted to rest. C, C, are uprights securing the platform to the girders D of the ceiling, while C' C' are diagonally-arranged supporting arms which extend from the upper ends of the uprights C C to the outer edge of the platform B, whereby said platform is supported at its outer edge from the girders D. E is the wall of the room in which the platform is suspended. One side of the lower portion B of the platform is in contact and rests against the wall E. F is the floor; G are the girders under the floor. Each of the arms C and the arm C' connected thereto constitute a hanger, one of the latter being applied to the platform proper B adjacent each end thereof, and it will also be observed that the arms C and C' of each hanger have a common point of connection with the girders D, whereby the platform may be suspended from the latter solely by the hangers.

In Fig. 2, the lower portion B of the platform is shown as secured to the wall E by

means of the rod H passing through said wall and secured on the other side of the wall by means of the screws I.

The underlying principle of this my invention resides therein that a swinging platform is secured with the upper part to the ceiling of the room in which it is placed, and is in contact or rests with part of the lower portion against the wall of the space in which it is located. Through this arrangement the vibrations are taken up by the solid wall and therefore are not transmitted to the floor or other parts of the building. I can state here that I have produced a platform of substantially the same construction and that in the space in which said platform was located vibrations were not noticeable. I do not claim here any means of changing the position of said platform, as such adjustable means are shown and claimed in application, Serial No. 252,058, filed March 25th, 1905.

Having now described my invention, what I claim as new and desire to secure by Letters Patent is:—

1. A platform for heavy machinery adapted to be arranged adjacent to the floor of a room, in combination with hangers by which said platform is supported from the joists or girders of a floor above, said hangers being connected to said joists or girders adjacent to the point of support of the joists or girders in the wall of the building, and means in the plane of the platform for anchoring the latter to said wall, whereby the transmission of vibration of the machinery to the floor adjacent to which it is placed is prevented, the transmission of such vibration to the floor above being minimized by absorption of the vibration by the hangers and by the attachment thereof near the wall.

2. A platform for heavy machinery adapted to be arranged adjacent to the floor of a room, in combination with hangers by which said platform is supported from the joists or girders of a floor above, said hangers being connected to said joists or girders adjacent to the point of support of the joists or girders in the wall of the building, a rod in the plane of the platform and adapted to be passed through the wall for anchoring the platform to said wall, and means carried by said rod for holding the same in engagement with the wall, whereby the transmission of vibration of the machinery to the floor adja-

cent to which it is placed is prevented, the transmission of such vibration to the floor above being minimized by absorption of the vibration by the hangers and by the attachment thereof near the wall.

In testimony whereof, I hereby sign my name in the presence of two subscribing

witnesses, this twenty-sixth day of May, A. D. 1905.

ARNOLD NACKE.
